FISH HOLDING DEVICE

Frank W. Benton and Arthur C. Porterfield,
Wilson, N. C.

Application August 26, 1943, Serial No. 500,130

3 Claims. (Cl. 17—8)

This invention relates to a device for holding fish, and one of its objects is to provide a device for holding a fish by its head or tail while it is being scaled and cleaned, or for holding its head back of the gills to enable a fishhook to be removed from the mouth or the throat of the fish, or for use in place of a gaff hook to grip a hooked fish to lift him out of water after being brought in reach, and for many other analogous purposes.

Another object of the invention is to provide a device of this character which is simple and inexpensive in construction, reliable and efficient in use in enabling a fish to be gripped at the head, tail or about the body for convenience in performing different operations, and which may be readily and conveniently manipulated in use.

The invention consists in the novel features of construction, combination and arrangement of parts, hereinafter fully described and claimed, reference being had to the accompanying drawing, in which:

Fig. 1 is a view in side elevation of a fish holding device embodying our invention, showing in full and dotted lines the jaws in closed and fully opened positions.

Fig. 2 is a section on the line 2—2 of Fig. 1, looking toward the inner face of one of the jaws.

Fig. 3 is a cross-section on the line 3—3 of Fig. 1.

Fig. 4 is a perspective view of one of the toothed gripping plates removed from its jaw.

In carrying our invention into practice we provide a holding device comprising a pair of counterpart clamping jaws 1 and 2 which are formed at one end with substantially circular portions 3 and 4 arranged side by side and which are apertured for passage of a pivot pin, rivet or bolt 5 whereby the jaws are pivotally connected for opening and closing movements. From these portions 3 and 4 the relatively outer surfaces of the jaws are longitudinally curved or rounded toward their opposite or free ends to give the jaws a desired tapered formation and to provide outer surfaces of a form adapting them to be conveniently gripped in the hand of the operator to enable a firm hold thereon to be obtained and the device readily manipulated for gripping and releasing operations.

Disposed between the inner faces of the jaws adjacent to their pivoted ends is a U-shaped spring 6 for normally holding the jaws spread apart. This spring may be made of spring metal plate or spring wire, as desired. In the form shown the spring is made of a spring metal plate bent into U-shape with its return portion 7 ar-

ranged adjacent the pivoted ends of the jaws and its arms 8 and 9 extending forwardly therefrom and bearing against the inner faces of the respective jaws. One of these arms, as the arm 8, is fixed to the jaw 2 by a pin or other suitable fastening member 10, while the other arm 9 is formed with a longitudinal slot 11 for the passage of a pin or other suitable fastening member 12, whereby said arm 9 is slidably connected to the jaw 1 to allow relative shifting movements between such arm and the spring in the opening and closing movements of the jaws. With this construction the jaw 2 may be considered as a stationary jaw and the jaw 1 as a movable jaw movable under pressure toward the jaw 2 against the resistance of the spring and movable away from the jaw 2 by reaction of the spring when the pressure on the jaw 1 is relaxed or removed.

Mounted upon the inner faces of the jaws between their transverse centers and free ends are toothed gripping elements 13 and 14. Each of these elements comprises an oblong rectangular plate secured to its jaw by suitable fastening members 15 and having its longitudinal side edges 16 and its front transverse edge disposed in alignment with the side edges and front edge at the free end of the jaw. Each plate has its front edge bent at an angle thereto and formed to provide a row of triangular gripping teeth 17, the teeth of the plates 13 and 14 being arranged to project toward each other for cooperative gripping action when the jaws are closed. Each plate is also provided in rear of its teeth 16 with two sets or groups of integral triangular teeth 17 bent therefrom and arranged in staggered order, each group comprising a front single centrally disposed tooth and two teeth disposed in rear thereof in transverse alignments and on opposite sides of the longitudinal center of the plate, said groups being placed one in rear of the other and at different distances from the tooth row 16. The arrangement is thus such that the teeth 16 may be used alone for a gripping action or in connection with the first set of teeth 17 or with both sets of teeth 17 on the jaws, according to the portion of the fish to be grasped for a firm holding action. Teeth may be arranged in different order, if desired.

In the use of the device, the device is grasped in the hand and operated like a pair of tweezers to grip a desired portion of the fish. In gripping a fish by the tail in scaling the front gripping teeth 16 are used. In gripping a fish by the head while scaling and cleaning it, holding its head back of the gills while removing a fishhook from

the mouth or throat of the fish, the front teeth 16 and front group of teeth 17 are used. In gripping a fish about the head or middle or other portion of the body all of the teeth may be used to secure a firm hold. All teeth are also used in employing the device in place of a gaff hook to grip a hooked fish after bringing him to the surface of the water and alongside a boat in landing a large fish. The device may also be used for other purposes in handling fish and other objects which are to be held firmly while being manipulated or operated upon.

The construction described adapts the device to be economically made and readily and conveniently operated and also adapts the jaws, if desired, to be made of wood, metal or plastic materials, to which the gripping plates may be fastened in the manner shown or in any other suitable manner. The gripping plates may be formed by stamping them from sheet metal or in any other suitable manner and, while the construction thereof shown is preferred, other forms preserving their structural merits may be employed. It will also be understood that, while the general construction of the device as disclosed is preferred, changes in the form, construction and arrangement of its parts, falling within the scope of the appended claims, may be made without departing from the spirit or sacrificing any of the advantages of the invention.

Having thus described our invention, we claim:

1. A fish holding device comprising a pair of

independent clamping jaws pivotally connected at one end for opening and closing movements, springs means disposed between the jaws adjacent the pivoted ends thereof for normally holding the jaws open, and a metallic gripping plate secured to the inner face of each jaw between the free end of the jaw and spring and spaced from the latter, each plate being provided with a transverse row of integral gripping teeth struck up therefrom and disposed in alinement with the free end of the jaw and groups of gripping teeth arranged in staggered order and disposed at different distances from the free end of the jaw.

2. A fish holding device comprising a pair of clamping jaws having substantially circular, flat disk-shaped portions at one end arranged in parallel relation and pivotally connected to couple the jaws for opening and closing movements, a U-shaped spring disposed between the jaws adjacent the pivoted ends thereof with its bight portion abutting against said ends and its arms projecting therefrom toward the free ends of the jaws, one of said arms being fixed to one of the jaws and the other arm being slidably connected with the other jaw, and gripping plates secured to the inner faces of the jaws and provided with gripping teeth bent therefrom and arranged at different distances from the free ends of the jaws and in advance of and spaced from the arms of the spring.
